UNITED STATES PATENT OFFICE.

CHARLES A. MILLIGAN, OF SOMERVILLE, AND MICHAEL J. KILLION, OF BOSTON, MASSACHUSETTS, ASSIGNORS TO THE EXCELSIOR SELF-LEVELING BERTH AND AUTOMATIC LADDER COMPANY, OF PORTLAND, ME.

SHIP'S BERTH.

SPECIFICATION forming part of Letters Patent No. 298,012, dated May 6, 1884.

Application filed February 7, 1884. (No model.)

To all whom it may concern:-

Be it known that we, CHARLES A. MILLIGAN and MICHAEL J. KILLION, respectively of Somerville, in the county of Middlesex, 5 State of Massachusetts, and Boston, in the county of Suffolk, State of Massachusetts, have invented a certain new and useful Improvement in Ships' Berths, of which the following is a description sufficiently full, clear, and exact to enable any person skilled in the art or science to which said invention appertains to make and use the same, reference being had to the accompanying drawings, forming a part of this specification, in which—

15 Figure 1 is an isometrical perspective view of our improved berth; Fig. 2, a top plan view of the same, showing the crib; Fig. 3, a vertical longitudinal section of the berth and crib; Fig. 4, an end view of the anti-friction journal; Fig. 5, a vertical longitudinal section of the journal; Fig. 6, a sectional view, showing the method of hanging the crib; and Fig. 7, a vertical transverse section of the berth and crib and a side elevation of the rack.

25 Like letters and figures of reference indicate corresponding parts in the different figures of the drawings.

Our invention relates to that class of ships' berths which are adapted to swing or are self-leveling; and it consists in a novel construction and arrangement of the parts, as herein-after more fully set forth and claimed, by which a simpler, cheaper, and more effective device of this character is produced than is 35 now in ordinary use.

The nature and operation of the improvement will be readily understood by all conversant with such matters from the following explanation.

40 In the drawings, A A represent the end walls of the state-room, B the berth, and C the crib.

The berth in horizontal cross-section is rectangular in form, has a curved bottom, a, and 45 its front side board preferably constructed slightly higher at either end than it is in the center. It is suspended in the state-room on journals D—one at either end—the journals being respectively provided with dovetail flanges

b, which are inserted in corresponding vertically-arranged dovetail grooves d, formed in the head and foot boards of the berth. The construction of the journals is best seen in Fig. 5, in which E is a socket secured in the wall of the state-room by the screws f, and G a screw cap, which is secured to the outer end of the stud j. This cap is provided with an annular groove, g, on its inner face, and there is also a corresponding annular groove, h, formed in the body of the journal at the base of the stud, a series of friction-rollers, i, being arranged to work in these grooves, the rollers projecting slightly beyond the cap G and base in which the groove h is formed. The interior of the socket E is threaded, and a correspondingly-threaded bushing or thimble, H, is screwed into the socket, the rollers i resting in this thimble, which may be readily replaced when worn out, and thus preserve the socket.

The crib is provided with a head-board, k, 70 foot-board, l, and laterally-inclined side rails, m. Its bottom is curved to conform to the curvature of the bottom of the berth, and is composed of the center rails or slats, p, suspended on bands q, attached to the side rails, 75 m. Each of the side rails is secured to the head and foot boards k l, and is provided with a bar, t, having a stud, v, which projects horizontally beyond the side of the crib, and is supported on a rod, w, the rod being suspended 80 on coiled springs x, disposed in a casing, y, in the side board of the berth.

A curved segment or toothed rack, J, is disposed beneath the head of the berth, being securely attached to the end wall of the state-room, and fitted to slide vertically in proper ways on the inner side of the head-board of the berth there is a locking-bar, K.

A horizontally-arranged lever, L, is pivoted at z to the head-board of the berth, the inner 85 end of this lever being jointed to the upper end of the bar K, and its outer end to the end of a bar, M. The bar M is arranged horizontally and pivoted at 5 to the plate 10, the plate being attached to the inner face of the 90 front side board of the berth.

A vertically-arranged hand-lever, N, is pivoted at 7 to a plate, 8, the plate being also

attached to the inner face of the front side board of the berth. (In Fig. 3 the front side board being represented as removed, the plates 8 and 10 are necessarily represented as detached therefrom.) The lever is curved below its pivot 7 nearly to its lower end, as seen at 12, and is provided with a headed stud or projection, 14, which is fitted to work in a slot, 6, in the lever M. A C-spring, 15, is placed between the bottom of the crib and the bottom of the berth, in such a position as to come about under the hips of the occupant of the crib, the supporting studs *v* being so disposed as to make the center of gravity and center of motion coincident, or as nearly so as possible.

In the use of our improvement, to lock the berth the upper end of the lever N is pulled toward the head of the crib, causing the curve 12 on said lever to depress the outer end of the lever M, and thereby elevate the outer end of the lever L and force the bar K into engagement with the rack J, as shown in Fig. 3, the berth being unlocked by pushing the upper end of the lever in the opposite direction, or toward the foot of the crib, until its head 14 strikes the lower side of the lever M, thereby elevating its outer end, depressing the outer end of the lever L, and disengaging the bar K from the rack J, as shown in Fig. 7.

It will be obvious that the curve 12 may be placed on the opposite side of the lever N, if desired, and accomplish the same results, the lever being moved accordingly to lock or unlock the berth.

As it is essential to construct the berth as long as possible, or so that it will fill the state-room between the end walls, A, the detachable flanged journals D and grooves *d* are used, thereby enabling the journals to be

readily attached to the berth after the berth is placed in position between the walls, which is accomplished by first inserting the journals in the sockets E and then raising the 45 foot berth until the flanges on the sockets enter the lower ends of the grooves, and dropping it into position.

We do not confine ourselves to using the channel bar *w*, spring 15, bushing H, or two springs, 50 *x*, as these features may be varied as desired. The form of the lever N and bottom of the crib C may also be varied and accomplish substantially the same result.

Having thus explained our invention, what we claim is—

1. In a self-leveling ship's berth substantially such as described, the lever N, pivoted to the side of the berth, and provided with the bend or cam 12, and headed stud 14, in combination with the pivoted lever M, and means for locking the berth, substantially as specified.

2. In a self-leveling ship's berth substantially such as described, the berth B, provided with the dovetail grooves *d*, for receiving the beveled or dovetailed flange on the journal D, substantially as specified.

3. The improved self-leveling ship's berth herein described, the same consisting of the berth B, provided with the sockets E, bushings H, grooves *d*, springs *x*, bar *w*, and rack J, the crib C, provided with side rails, *m*, studded bars *t*, slats *p*, bands *q*, levers L M N, bar K, flanged journal D, cap G, and rollers *i*, 75 feet constructed, combined, and arranged to operate substantially as shown and described.

CHAS. A. MILLIGAN.
MICHAEL J. KILLION.
